[57] **CLAIM**

We claim the ornamental design for an adjustable flat panel mounting bracket, as shown and described.

DESCRIPTION

FIG. 1 is a front elevation view of the adjustable flat panel mounting bracket showing our new invention;
FIG. 2 is a back elevation view thereof;
FIG. 3 is a left side elevation view thereof;
FIG. 4 is a right side elevation view thereof;
FIG. 5 is a top plan view thereof; and,
FIG. 6 is a bottom plan view thereof.

The broken line drawing of a flat panel in all figure views is for illustrative purposes only and forms no part of the claimed design.
